UNITED STATES PATENT OFFICE.

BENJAMIN F. SPRUILL, OF BROOKLYN, NEW YORK.

DESIGN FOR A SCRAPER.

SPECIFICATION forming part of Design No. 19,979, dated July 1, 1890.

Application filed June 3, 1890. Serial No. 354,135. Term of patent 14 years.

To all whom it may concern:

Be it known that I, BENJAMIN F. SPRUILL, of Brooklyn, in the county of Kings and State of New York, have invented a new and Improved Design for Scrapers, of which the following is a full, clear, and exact description.

The leading feature of my design consists in the under surface of the handle-block of the scraper, said under surface presenting defining lines tapering in opposite directions upwardly and outwardly toward the ends of the handle-block.

A indicates the handle-block of the scraper, and B the blade thereof. The contour of the

handle is on the under surface oppositely-tapering toward the ends, as shown and indicated at *a a*. The blade presents a straight outline that departs from the outline of the under surface of the handle-block in a downward direction. 15 20

I claim—

The design for a scraper herein shown and described.

BEN. F. SPRUILL.
